UNITED STATES PATENT OFFICE

LOREN C. TUCKER, OF SYRACUSE, NEW YORK, ASSIGNOR TO THE PROSPERITY COMPANY, INC., OF SYRACUSE, NEW YORK, A CORPORATION OF NEW YORK

PRESSURE MEMBER FOR PRESSING MACHINES

Application filed July 11, 1927, Serial No. 204,720. Renewed August 30, 1929.

This invention relates to pressing machines as garment and laundry pressing machines and has for its object a particularly simple, efficient and economical pressure member by which the pressure is delivered 5 equally throughout the pressure face and by which inequalities in thicknesses of the article being pressed or inequalities due to inaccuracies in the pressing machines are automatically compensated for.

The invention consists in the novel features and in the combinations and constructions hereinafter set forth and claimed.

In describing this invention, reference is 15 had to the accompanying drawings in which like characters designate corresponding parts in all the views.

Figure 1 is a vertical lengthwise sectional view of this pressing member, the contiguous 20 parts of the pressing elements as the head and buck of a pressing machine being shown.

Figure 2 is a plan view of this pressure member.

Although this pressure member is intended 25 primarily for garment and laundry pressing machines, it will be understood that it is applicable to other forms of pressing machines.

In the illustrated embodiment of my invention, this pressure member is shown as 30 applied to the lower element or buck 1 of a garment or laundry pressing machine in which the head 2 moves toward and from the buck by any suitable mechanism. It will be understood however, that the head 2 does 35 not apply pressure but merely has an opening and closing movement for the purpose of permitting the operator to arrange the garment or other article on the pressure member and for removing the same there-

40 from, the pressure being applied by the pressure member when the head is brought down close to the work thereon and locked in such position. As the construction and operation of garment and laundry pressing machines 45 is well known, further description is thought to be unnecessary.

The pressure member comprises a plurality of movable elements which deliver the pressure, these elements being preferably 50 sliding plungers, the outer end faces of

which constitute the presser face of the pressure member and means as hydraulic means for applying pressure to the inner ends of said plungers.

The pressure member here illustrated 55 comprises a hollow body 3 divided by an expandable element as a flexible or resilient diaphragm 4 into upper and lower chambers 5 and 6.

7 designates the plungers which are movable through guide openings 8 in the upper wall of the body with their lower ends engaging the diaphragm 4. These plungers are preferably spaced as close together as possible so that their end faces 9 constitute a 65 substantially continuous presser face.

The body 3 is placed upon the buck and the chamber 6 below the diaphragm filled with a fluid as water or oil and connected by a pipe 10 extending through the buck to 70 a suitable source of supply of a pressure as compressed air or water pressure to apply pressure to the fluid in the chamber 6. The application of pressure to the fluid in the chamber 6 is controlled in any suitable manner. The faces 9 of the plungers are also 75 usually covered with a suitable padding 11.

In operation, after the garment has been placed on the padding 11 and the head 2 brought down and locked in closed position, 80 the pressure is applied through the liquid in the hydraulic chamber 6 expanding the diaphragm 4 causing it to push the plungers 2 upwardly and apply pressure. Those plungers underlying the thicker portions of the 85 garment as seams, buttons etc., will obviously not be depressed as much as the other plungers but the pressure will be equalized through the hydraulic fluid.

Also, if the operator's hand for any reason 90 becomes caught between the head 1 and the garment, the plungers underlying the hand will be depressed inwardly farther than the other plungers without gripping or injuring the hand. The hand may be burned as the 95 head 2 is usually formed hollow and heated but no injury will result because of the pressure. In pressing machines now used, the hands of the operator are not only burned but also crushed.

This pressing machine element is particularly advantageous in that pressure can be applied to pressing machines in a simple and economical manner without more or less complicated mechanical motion transmitting means and motors etc., and in fact, water pressure can be used to apply pressure to the fluid in the chamber 6.

What I claim is:

1. A pressing machine comprising cooperating pressing elements, one of which is movable toward and from the other, one of said elements being formed hollow and provided with a diaphragm therein dividing the same into two compartments, one of said compartments being a pressure chamber and the other compartment being provided with a plurality of closely arranged plungers movable therethrough, the inner ends of the plungers engaging the diaphragm, the outer end surfaces of the plungers constituting the pressure face of said element.

2. A pressure member for pressing machines comprising a hollow body having a diaphragm dividing the same into two compartments, one compartment being a pressure chamber and the other compartment having a plurality of sliding plungers guided therein and coacting at their inner ends with the diaphragm and having their outer ends located outside of the chamber for transferring the movement of the diaphragm.

3. A pressure member for pressing machines comprising a hollow body having a diaphragm dividing the same into two compartments, one compartment being a pressure chamber and the other compartment having a plurality of sliding plungers guided therein and coacting at their inner ends with the diaphragm and having their outer ends located outside of the chamber for transferring the movement of the diaphragm, said plungers being located close together and the end faces thereof forming the pressure face of said member.

4. A pressing machine member comprising a body, a plurality of closely spaced plungers slideable through a wall of the body, the outer ends of said plungers constituting the pressure face of said member and power means within the body acting on the inner ends of the plungers and common to all of the same and serving to equalize the pressure on the plungers when some are depressed more than others.

5. A pressing machine member comprising a body, a plurality of closely spaced plungers extending through a wall of the body, the outer ends of said plungers constituting the pressure face of said member and hydraulic means within the body acting on the inner ends of the plungers, said pressure means being common to all the plungers whereby there is an equalizing action between the plungers.

6. A pressing machine member comprising

a body, plungers slideable through a wall of the body and delivering the pressure and pressure means within the body and acting on the inner ends of the plungers.

7. A pressing machine member comprising a body, plungers slideable through a wall of the body and delivering the pressure and pressure means within the body and acting on the inner ends of the plungers, said means comprising an expansible element in the body forming a pressure chamber for a hydraulic fluid.

8. A pressing machine element comprising a hollow body provided with a diaphragm, the body on one side of the diaphragm being a pressure chamber and a plurality of pressure delivering parts mounted on the other side of the diaphragm and having portions spaced apart from the diaphragm and forming a supporting surface for the article to be pressed.

9. A pressing machine comprising cooperating pressing elements, one of which is movable toward and from the other, one of said elements being formed hollow and provided with a diaphragm forming a pressure chamber on one side of the diaphragm and pressure delivering parts on the other side of the diaphragm having their inner ends pressing against the diaphragm and having outer portions spaced apart from the diaphragm, the outer portions normally forming an even supporting surface for the article to be pressed.

10. A pressing machine member comprising a plate, a plurality of closely spaced plungers slideable through said plate, the upper ends of said plungers providing the pressing surface of the pressing machine member, pressure producing means acting on the inner ends of the plungers and a fluid pressure-chamber having a flexible top in contact with the inner ends of the plungers for exerting pressure upon said plungers.

11. A pressing machine member comprising a plate, a plurality of closely spaced plungers slideable through said plate, the upper ends of said plungers providing the pressing surface of the pressing machine member, and a common pressure producing means acting on the inner end of each of the plungers.

In testimony whereof, I have hereunto signed my name, at Syracuse, in the county of Onondaga and in the State of New York, this 30th day of June, 1927.

LOREN C. TUCKER.

CERTIFICATE OF CORRECTION.

Patent No. 1,780,650.

Granted October 28, 1930, to

LOREN C. TUCKER.

It is hereby certified that error appears in the printed specification of the above numbered patent requiring correction as follows: Page 2, lines 62 to 64, claim 5, strike out ", said pressure means being common to all the plungers whereby there is an equalizing action between the plungers" and insert same to follow after "plungers" line 69, claim 6; and that the said Letters Patent should be read with these corrections therein that the same may conform to the record of the case in the Patent Office.

Signed and sealed this 9th day of December, A. D. 1930.

(Seal)

M. J. Moore,
Acting Commissioner of Patents.
